United States Patent Office

Des. 208,587
Patented Sept. 12, 1967

208,587

OPERA GLASS

Willy Herold, Munich, Germany, assignor to Optische
Werke G. Rodenstock, Munich, Germany

Filed Dec. 28, 1966, Ser. No. 5,206

Term of patent 14 years

(Cl. D57—1)

FIG.1

FIG.2

FIG.3

FIG.4

FIG.5

FIG. 1 is a perspective view of an opera glass embodying my new design;

FIG. 2 is a rear view thereof in elevation;

FIG. 3 is a top plan view thereof;

FIG. 4 is a bottom plan view thereof; and

FIG. 5 is a left end view thereof in elevation.

I claim:

The ornamental design for an opera glass, as shown.
